INTERNAL GRINDING MACHINE

John William Parker, Grosse Pointe, Mich.

Application July 7, 1955, Serial No. 520,420

14 Claims. (Cl. 51—95)

This invention relates to machines and more particularly to grinding machines or the like.

While the principles of the invention are applicable to diverse types of power machinery, they are exemplarily embodied in an internal grinder primarily employed to grind an aperture or socket in a workpiece to a precise diameter or taper.

The features herein described and claimed evolved from an effort to provide the industry with a compact, relatively low cost grinder suitable for single-piece manually controlled grinding operations, while at the same time adapting the grinder to semiautomatic operation so that the smaller shop, with a reasonable investment, can produce quantities of identical parts on a competitive basis.

In general, in the disclosed embodiment of the invention, a workpiece is rotated about and reciprocated along the longitudinal axis of the aperture or socket which is to be ground, by means of a workhead mounted upon a reciprocating table. A grinding wheel is positioned to engage that aperture or socket and is independently rotated about its longitudinal axis. A cam-actuated sizing unit, driven by the reciprocating table, supports and incrementally feeds the grinding wheel into the work, transversely of the line of table reciprocation, on a cyclic basis. The point in the stroke of the table at which the incremental feed occurs, and the amplitude of the increment, may both be adjusted.

The sizing unit as a whole may also be moved transversely of the line of table reciprocation for manually controlled grinding and for initial setting preliminary to semiautomatic operation.

A wheel dresser is employed not only to insure that the surface of the grinding wheel is in proper condition, but also as a primary element of the sizing control in semiautomatic operation of the mechanism.

A feature of the invention is an improved automatic crossfeed mechanism.

Another feature of this invention is an improved means for actuating a crossfeed mechanism by the reciprocations of a longitudinal feed table.

Another feature of this invention is an improved mechanism for applying balanced forces to move a rotating spindle evenly, precisely and without binding.

A further feature of this invention is a circuit arrangement for automatically initiating and terminating the operation of driving motors as a function of the cyclic operation of a crossfeed mechanism and as a function of the position of a reciprocable table.

Another feature of this invention is an improved method of semiautomatically grinding a plurality of workpieces.

The detailed nature of the foregoing features, and other features of the invention, will be perceived from the following detailed description of an embodiment of the invention when read with reference to the accompanying drawings in which:

Figure 1 is a perspective view of an internal grinding machine embodying the principles of the invention;

2

Fig. 2 is an enlarged, fragmentary, front elevational view of a portion of the mechanism represented in Fig. 1;

Fig. 3 is a sectional view taken substantially along the line 3—3 of Fig. 1, showing the automatic sizing unit in side elevation and a portion of the mechanism for driving that unit;

Fig. 4 is an enlarged perspective view of the wheel dresser shown in Fig. 1;

Fig. 5 is a sectional view taken substantially along the line 5—5 of Fig. 3;

Fig. 6 is an enlarged view of the actuating cam mechanism of the automatic sizing unit;

Fig. 7 is a sectional view taken substantially along the line 7—7 of Fig. 3;

Fig. 8 is a fragmentary perspective view looking generally in the direction of the arrow 8 in Fig. 1 of the drawings;

Fig. 9 is a sectional view taken substantially along the line 9—9 of Fig. 3;

Fig. 10 is a sectional view taken substantially along the line 10—10 of Fig. 9; and

Fig. 11 is a representation of an electrical system for controlling the motors represented in Fig. 1.

While the machine shown in Fig. 1 of the drawings is adaptable to a variety of uses, and while the principles of the invention are even more broadly applicable, it is assumed that an internal grinding operation is to be performed upon each of a plurality of workpieces. A workpiece is normally mounted in a chuck 14 so that the aperture or socket therein which is to be ground and the chuck have a common longitudinal axis. Chuck 14 is rotatively driven by a conventional workhead 16, including a motor 18.

The workhead 16 is rigidly mounted, through its base 20, to a table 22. Table 22 is supported upon slides 24 and 26 (Fig. 3) on a base 28 so that the table 22, and hence the workhead 16, may be reciprocated relative to the base 28.

Reciprocation of the table 22 relative to the base 28 may be performed manually or automatically. Manual control of the movement of the table 22 is exercised through a hand-feed wheel 30 which drives the table through a conventional rack-and-pinion arrangement (not shown). Alternatively, the table 22 may be reciprocated relative to the base 28 by means of a table drive motor 32 which is connected to drive, through conventional gearing not shown, a wheel 34. Wheel 34 is provided with an eccentrically mounted pin 36 engaged by a link 38 which serves to oscillate a bellcrank 40 about a pivot pin 42. To transform the oscillatory motion of bellcrank 40 into translational motion of the table 22, the upper end of bellcrank 40 is clasped between a stop 44 and a latch 46 (Fig. 2), both of which are secured to but adjustable along the length of the table 22. By shifting the positions of stop 44 and latch 46, both the length of the stroke and the position of the stroke may be adjusted.

Latch 46 is mounted upon a bar 48 which is vertically slideable relative to its support member 49. Latch 46 is biased downwardly, as shown, by gravity supplemented, if necessary, by a biasing spring (not shown). The support member 49 is attached to the table 22 and may be adjustably positioned along the length thereof. The upper arm of bellcrank 40 may be momentarily disengaged from the latch 46 by sliding the bar 48 upwardly by means of the handle 50. Upon such disengagement, the table 22 may be moved to the left (Fig. 1) by the handwheel 30 to a limit position to permit loading a workpiece into the chuck 14 or to permit dressing of the grinding wheel, as will be noted.

A bracket 47 (Fig. 2) is also mounted upon the edge of the table 22 with its position preferably being adjustable along the length of the table. A trip lever 52 is

pivotedly and pendently supported on the bracket 47 by a pin 53. Lever 52 can freely move through an arc in a counterclockwise direction, but clockwise movement is prevented by a stop pin 55 mounted on bracket 47.

When table 22 is moved to the left, as noted above, trip lever 52 strikes the actuating arm 51 of limit switch LS1. However, lever 52 does not actuate limit switch LS1 since in this direction lever 52 freely pivots, rides over arm 51, and drops back to its normal position (Fig. 2) upon clearing and moving to the left of arm 51.

When table 22 is again moved to the right by hand-wheel 30, trip lever 52 again strikes actuating arm 51 and since stop 55 (Fig. 2) prevents clockwise rotation of lever 52, arm 51 is actuated to operate limit switch LS1. In being so actuated, arm 51 is pivoted in a clockwise direction (Fig. 1) and is cammed out of the path of lever 52 so that the table 22 can continue to move to the right. Thus, limit switch LS1 is not operated as table 22 is moved to the left, but is momentarily operated as table 22 is returned to the right.

As table 22 is moved further to the right, the cam surface on the lower right-hand face of latch 46 (Fig. 2) strikes the upper end of bellcrank 40, driving latch 46 upwardly and over the bellcrank end. At or prior to the point at which the upper end of crank 40 strikes stop 44, latch 46 will have cleared the bellcrank and will restore to the shown latching position.

If the length of the requisite stroke is longer than that provided by the reciprocator mechanism including bellcrank 40, a power feed mechanism may be provided of any suitable type known in the art. Thus, motor 32 may be of the reversible type, with its direction of rotation controlled by limit switches LS1 and LS3 which may be actuated in any appropriate manner at each end of a selected stroke.

It is customary to supply coolant to the work during machine grinding operations and means including coolant pump and motor 54 may be provided to supply an appropriate coolant liquid either as a stream directed at the grinding wheel and work exteriorly of the apparatus, or as a stream flowing through a central orifice (not shown) through the workhead 16 and chuck 14 to flood the inner surface of the workpiece.

The grinding wheel 58 (Figs. 1 and 8) is both rotated and crossed by means including an automatic sizing unit 60. Unit 60 is supported upon ways 61 (Fig. 8) along which it may slide in a direction perpendicular to the direction of motion of the table 22. Ways 61 are formed on the upper surface of a cross-feed bed 29, integral with base 28. The unit 60 is moved upon the ways 61 by means including a vernier cross-feed mechanism 63 (Fig. 1). This cross-feed mechanism, which may be of any conventional type well known in the art, may be employed during manually controlled grinding operations and is also employed to establish an initial position of the automatic sizing unit 60 preparatory to automatic operation of the machine.

The automatic sizing unit 60 comprises a body casting 62 including a pair of forwardly extending, parallel, annular support members 64, serving as a bracket, as may best be seen in Figs. 8 and 9 of the drawings. Each annular support member 64 carries a bearing 66 affixed within its central bore by means such as machine screws 68. The reduced end portions of a shaft 69 are rotatably seated in the two bearings 66. The bearings 66 are preferably closed by means such as plugs 70, one of which may be tapped to accept an oiler 72 arranged to flow oil through a channel 74 in the shaft 69 and thence to the bearing surfaces.

Shaft 69 supports a rocker assembly including a rocker casting 76 the upper end of which is bored to accept the shaft 69 and is of appropriate length to fit between the annular support members 64. As shown in Fig. 9, the rocker casting 76 is preferably non-rotatively associated with the shaft 69, by means such as keys 78, to insure

that the relative rotation will occur between the shaft 69 and the surfaces of the bearings 66.

At its lower end, the rocker casting 76 is provided with an enlarged, bored, longitudinally split spindle housing portion 80 (Figs. 1, 3, 8 and 10). A spindle assembly 82 (Fig. 8), including a spindle 84 and a pulley 86 (Fig. 10), as well as appropriate bearings (not shown) is clamped within the spindle housing 80 by means such as machine screws 88. The spindle 84 supports the grinding wheel 58 (Fig. 8).

To rotatively drive the spindle assembly 82, a motor 92 is mounted upon the body casting 62 and is provided with a driving pulley 94 coupled to the spindle pulley 86 by a belt 96 (Figs. 3 and 10). To maintain the proper tension upon the belt 96 while permitting the use of spindle pulleys 86 of various sizes, and to maintain proper belt tension despite shifting of the distance between motor pulley 94 and spindle pulley 86 during cross-feeding, an idler 100 is rotatively mounted upon a support arm 102. Support arm 102 is rotatably mounted upon a pin 104 affixed to the body 62 by means of a bracket 106.

The spindle assembly 82, the spindle housing 80 and the rocker 76 are rocked on the longitudinal axis of the shaft 69 in a controlled, automatic manner to produce automatic cross-feeding. The rocker 76 and spindle housing 80 are firmly biased in a counterclockwise direction (Fig. 10), i. e., towards the body casting 62. A spring 110 is seated within a horizontal socket 112 formed in the rocker 76. A bolt 114 extends through a bore in the rocker 76 which is coaxial with the socket 112, and through an aligned bore in a web 116 of the body casting 62, and is there secured by a nut 118. The head of the bolt 114 engages a washer 116 which thereby serves to compress spring 110 to cause a force to be exerted to force the rocker 76 and the spindle housing portion 80 in a counterclockwise direction, towards the body 62. The bolt 114 and spring 110 are preferably centered between the support members 64, as is shown in Figs. 1 and 9 of the drawings.

Rest buttons 120 (Figs. 9 and 10) are seated within individual sockets 122 near each end of the spindle housing 80, the longitudinal axes of the buttons 120 preferably but not necessarily, being coplanar with each other and with the longitudinal axis of the spindle assembly 82. The head of each of the rest buttons 120 engages an individual actuating pin 124 slidably mounted in horizontal apertures in the body casting 62. The rear end of each of the actuating pins 124 engages an individual flat 126 formed in an otherwise right-circular cylindrical actuating shaft 128. Bearings 132 and 134, seated within aligned apertures in the side walls of the body casting 62, rotatably support the actuating shaft 128. The shaft 128 is prevented from moving in translation along its longitudinal axis in one direction by a thrust washer 138 (Fig. 9), fastened to the shaft 128 by a set screw 140 or equivalent means, and in the other direction by engagement of an actuating arm, integral with the shaft, with the side of the body casting, as will be noted.

As may best be seen in Fig. 10 of the drawings, the actuating pins 124 engage the flats 126 at a point or area vertically offset from the longitudinal axis of the shaft 128. Hence, as the shaft 128 is rotated in a clockwise direction (Fig. 10), forces are exerted to move the actuating pins 124 to the left, the distance of movement of the actuating pins 124 being determined by the extent of the aforesaid offset and by the angle through which the shaft 128 is rotated. It is important to precision operation that both actuating pins 124 exert equal forces to rotate and hold the spindle housing 80. This is exemplarily accomplished by making the two flats 126 coplanar, by making the distances between the longitudinal axis of the shaft 128 and the points or areas of contact between the actuating pins 124 and the flats 126 equal to one another, by making the longitudinal axes of the

actuating pins 124 parallel with one another, and by making the shapes of those ends of the two actuating pins 124 which engage the flats 126 the same. The ends of the actuating pins 124 engaging the flats 126 may be spherical or conical to provide point contact, may be cylindrical to provide line contact, or may be appropriately formed to provide area contact at a selected position of the shaft 128. The two rest buttons 120 and the two actuating pins 124 need not be identical pairs. However, with the longitudinal axes of the shaft 128, the shaft 69, and the spindle assembly 82 all parallel to one another, it is important that when there is solid mechanical contact between the spindle housing 80, one of the rest buttons 120, the associated actuating pin 124 and the associated flat 126, there should concurrently be equivalent mechanical contact between the spindle housing 80, the other rest button 120, the other actuating pin 124 and the other flat 126. This may be accomplished, for example, by lapping the longer of the noted combinations until it is exactly the same length as the shorter, or by manufacturing all parts to close tolerances.

It will therefore be seen that by rotating shaft 128 in a clockwise direction (Fig. 10), the actuating pins 124 and rest buttons 120 are moved to the left to exert balanced forces upon the spindle housing 80 to rotate the rocker assembly 76 about the longitudinal axis of the shaft 69. These balanced forces are opposed by the restoring force of spring 110, which force, as before noted, is applied in a vertical plane centered between the vertical planes which include the longitudinal axes of the actuating pins 124. By virtue of this arrangement, there is no danger of binding or of uneven wearing which would tend to cock the spindle axis.

The rotation or oscillation of the shaft 128, and the consequent movement of the flats 126, is accomplished through an actuating arm 142 (Figs. 8 to 10) formed integrally with the shaft 128. In its preferred form, a flat 126 forms the forwardmost face of the arm 142, while the rest of the upper portion of the arm 42 is generally circular, but having a diameter greater than that of the shaft 128 to define a flange portion 144. This flange portion 144 (Fig. 10) abuts the face of the body castings 62 or, preferably, the edge of the bearing 134 in order to prevent translational motion of the shaft 128 in one direction, as previously mentioned.

A socket 146 is provided near the lower end of the downwardly depending portion of the arm 142 to accept a cam follower 148. The end of cam follower 148 is maintained in engagement with a cam 150 by means of a spring 152 (Fig. 10) which engages the forward face of the actuating arm 142 and which is mounted upon a spring guide 154 affixed to the body casting 62. Cam 150, the configuration of which will be hereinafter described, is mounted upon a cam shaft 158 and is prevented from rotating with respect thereto by means such as a key 160 (Fig. 9). Cam shaft 158 is rotatably supported by bearings 162 and 164, bearing 162 being mounted in a bearing sleeve 166 positioned in one wall of the body casting 62 and bearing 164 being mounted in a bearing sleeve 168 fixed within the aperture in the other wall of the body casting 62 by means of machine screws 170 or the like.

At the end of the cam shaft 158 upon which the cam 150 is mounted, the shaft is reduced in diameter and threaded to accept a nut 174. A pair of timing drums or discs 176 and 178 and a pair of washers 180 and 182 are sandwiched between the nut 174 and the outer face of the side wall of the body casting 62. The timing discs 176 and 178 are, in this fashion, secured to the cam shaft 158 and will rotate therewith. As may be seen in Fig. 8 of the drawings, disc 176 is provided, at one point in its periphery, with an extending or projecting finger 184 and timing disc 178 is provided at one point on its periphery with an extending finger 186. A limit switch LS2 (Figs. 8 and 9) is mounted to the body cast-

ing 62 by means of a mounting bracket 190. The actuating element 192 of switch LS2 extends to a point adjacent to and spans the breadth of both of the timing drums or discs 176 and 178. Consequently, as the shaft 158 is rotated, switch LS2 will be tripped whenever the actuating member 192 thereof is engaged either by the projecting finger 184 on timing drum 176 or the projecting finger 186 on the timing drum 178. Switch LS2 serves to terminate the rotation of both the workhead motor 18 (Fig. 1) and the table drive motor 32 in a manner and for a purpose hereinafter to be described.

The cam shaft 158 may be automatically rotated under the control of the motion of the table 22 (Fig. 1). Thus, a cam 200 (Figs. 1, 2 and 3) is mounted upon and moves with the table 22. Its position along the table is preferably adjustable for a purpose hereinafter to be noted. A rocker arm 202 is pivotally mounted relative to the base 28 by a bracket 204. As the table moves from the left to the right (Figs. 1 and 2) during each stroke, the cam 200 engages a roller 206 (Figs. 2 and 3) rotatably mounted upon the upper end of the rocker arm 202. As a result, the upper end of the rocker arm 202 is pivoted forwardly (counterclockwise in Fig. 3) and the lower end of that rocker arm is caused to move inwardly. The lower end of rocker arm 202 is bifurcated and apertured to accept a pin 208 which also engages an aperture in the end of a generally horizontally disposed rocker link 210 (Fig. 3). Rocker link 210 extends through an aperture in the bottom of a socket 212 seated within an aperture 214 in the forward wall of the hollow base portion 28. A compression spring 216 is trapped between the base of the socket 212 and a washer 218 mounted upon the rocker link 210 and abutting the rear face of the lower end of the rocker arm 202. As a result, the roller 206 at the upper end of the rocker arm 202 is continuously forced toward the table 22 in a position to be engaged by cam 200, the camming action overcoming the force exerted by spring 216.

40 Rocker link 210 extends through an aperture 220 formed in a vertical portion of the base 28 and is apertured to accept a pin 222 which also engages aligned apertures in the two legs of the bifurcated lower arm of a feed lever 224 (Figs. 3 and 5). Feed lever 224 45 operates in the nature of a bellcrank, pivoting about a pin 226 secured to the cross-feed bed 29. Pin 226 may conveniently be in the form of a cap screw engaging a tapped aperture in the bed 29. The generally horizontally disposed upper arm 228 of the feed lever 224 is longitudinally slotted to accept a threaded link pin 229 which also passes through a bushing 232 (Fig. 5) and is secured by a nut 234. Bushing 232 pivotally supports the lower end of a ratchet link 230. At its upper end, ratchet link 230 is rotatably attached, by means of a pin 238, to a feed bracket 240. As may best be seen in Fig. 7 of the drawings, the feed bracket 240 is rotatably supported upon the cam shaft 158 by means of a bearing 242, bearing 242 being retained upon the cam shaft 158 by means of a screw 244 engaging a tapped aperture in the end 60 of the cam shaft 158 and a washer 246 interposed the head of the screw 244 and the outer faces of the cam shaft 158 and the bearing 242.

65 It will be perceived in Fig. 3 of the drawings that the link pin 238 is eccentrically mounted relative to the axis of rotation of the feed bracket 240. Hence, during each stroke of the table 22, when the camming surface strikes the wheel 296, the rocker arm 202 is pivoted to drive the rocker link 210 a short distance rearwardly of the machine (to the right in Fig. 3), and this motion is communicated through the bellcrank feed lever 224 and the ratchet link 230 to rotate the feed bracket 240 through a small angle in a counterclockwise direction (Fig. 3). As the table 22 commences its return stroke, the camming surface 200 is moved away from the wheel 296

and the elements are restored to their normal positions, as shown, by the spring 216.

This normal position is defined by an adjusting screw 250 (Figs. 3 and 5) threadedly engaging a bracket 252 affixed to the cross-feed bed 29, and retained in selected position by a lock nut 254. Screw 250 is adapted to engage the lower surface of the arm 228 of the feed lever 224 thereby to adjustably establish a limit to the clockwise motion of the feed lever 224, and hence to establish the length of the stroke of the ratchet link 230 and the angle of rotation of the feed bracket 240.

A pawl 256 is pivotally mounted upon a pin 258 (Fig. 7) which extends through an aperture in the feed bracket 240 and is retained on the feed bracket by a washer 260 and nut 262. Pawl 256 is spring biased into engagement with the teeth on a ratchet 264 which is mounted upon the cam shaft 158. Means such as a key 266 is provided to prevent relative rotation between the cam shaft 158 and the ratchet 264.

As the feed bracket 240 is rotated through a small angle in a counterclockwise direction (Fig. 3), the engagement between the pawl 256 and the ratchet 264 causes the ratchet 264, and hence the cam shaft 158 (Fig. 7), to be rotated through the same angle. Upon the return stroke, the pawl 256 rides over the teeth of the ratchet 264 to assume its initial position, normally in engagement with another tooth, in preparation for further incremental rotation of the cam shaft 158. The ratchet 264, and hence the cam shaft 158, is prevented from rotating in a clockwise direction (Fig. 3) by means of a ratchet lock 270 pivotally mounted upon the body casting 62 and spring biased into engagement with the teeth of the ratchet 264.

It will now be perceived that the adjusting screw 250 in essence controls the size of the angle through which cam shaft 158 is rotated during each stroke of the work table 22 by controlling the number of teeth on the ratchet 264 which are traversed by the pawl 256 during its return stroke. In a pragmatic embodiment of the invention, as an example, the adjusting screw 250 may be positioned to permit variation in the angle of rotation of the cam shaft 158 from a minimum of $1\frac{1}{2}^{\circ}$ to 12° for each stroke of the table 22.

This incremental rotation of the cam shaft 158 causes the cam 150, keyed thereto, to similarly incrementally rotate, and this incremental rotation of the cam produces a selected cross-feed of the grinding wheel into the work, cam rise being translated into spindle movement by the cam follower 148, actuating arm 142 and actuating pins 124.

An exemplary configuration of the cam 150 is represented in Fig. 6 of the drawings. At the beginning of each cycle of operation, the cam is in a position wherein the cam follower 148 is in engagement with that portion of the cam surface labeled "load," i. e., between lines 276 and 278. This loading portion of the cam surface is preferably but not necessarily arcuate and is normally the area of minimum radius from the longitudinal axis of the cam shaft 158. As a result, the cam follower 148 is in its furthest position toward the rear of the machine (towards the left in Fig. 8, towards the right in Fig. 9). Hence, the spindle housing 80 and the grinding wheel 58 (Figs. 1 and 8) are both at their most rearward position with any given manual setting of the cross-feed wheel 63 (Fig. 1). The cross-feed wheel 63 is preferably initially adjusted so that when cam 150 is in this "load" position, the grinding wheel 58 is freely insertable within the bore of the workpiece which is to be internally ground.

During the "rough grind" portion of the cam 150 (Fig. 6), from line 278 to line 280 the distance between the longitudinal axis of the cam shaft 158 and the cam surface gradually increases. The difference between the distance from this center axis to the cam surface at the beginning of the rough grind, along lines 278 and the

10 distance at the end of the rough grind, along line 280, will be determined by the use to which the machine is being placed, e. g., the amount of material that must be removed from the inner surface of the workpiece, the expected variation in the rough internal diameters of the workpieces and the rate of rapid in-feed desired. As an example, in practice this may be in the order of 10 or 15 thousandths of an inch. The camming surface must vary by a factor greater than this under the disclosed preferred arrangement in view of the mechanical advantage resulting from the difference in the lever arm between the longitudinal axis of the shaft 128 (Fig. 10) and the actuating pin 124 and the distance between that longitudinal axis and the axis of the cam follower 148. As an example, this mechanical advantage may be in the order of 6 to 1, permitting the cam surfaces to be varied by a factor six times greater than the desired variation at the work.

Over the first "dwell" portion of the cam surface (Fig. 6), between lines 280 and 282, the surface is arcuate and marks the termination of the rapid in-feed. During the "dress" period, between lines 282 and 284, the cam surface is again preferably arcuate but the radius is less than that during the first dwell period so that the grinding wheel is backed off from the internal surface of the workpiece by a few thousandths of an inch to insure that there will be no engagement as the grinding wheel is withdrawn from the workpiece, as will be noted. During the "finish" period, between lines 284 and 286, the cam surface again slowly increases in radius so that the grinding wheel is slowly advanced a small distance to perform a final finish cut. During the final "dwell" period, between lines 286 and 276, the cam surface is preferably again arcuate to perform the finishing off or "sparking out" of the workpiece.

The cam 150 may be manually advanced through its cycle, or any portion of a cycle skipped, by rotating an adjusting knob 292. As may best be seen in Fig. 10 of the drawings, the adjusting knob 292 is attached to a shaft 294 by a pin 296, the base of the knob 292 resting upon a bushing 298 seated upon the upper end of a bored portion 300 of the body casting 62.

Shaft 294 is rotatably supported by a bearing 302 seated in a bracket 304 rigidly attached to the body casting 62. A miter gear 306 is pinned or otherwise affixed to the lower end of the shaft 294 and is engageable with a mating miter gear 308 (Fig. 9) retained upon the cam shaft 158 by pin 316. Hence, by rotating the knob 292, the gears 306 and 308 are rotated to rotate the cam shaft 158 and cam 150.

In internal grinding, the grinding wheel must be occasionally or regularly dressed in accordance with the degree of precision required. In the disclosed arrangement, a wheel dresser 315 is employed as a primary element of the automatic control of the grinding to finished size. The exemplary wheel dresser, as represented in Fig. 4 of the drawings, comprises a slotted base 316 provided with means (not shown) for supporting a shaft 318. A longitudinal bore in the dresser body 320 engages the shaft 318 and is rotatable thereon between an upright position, as shown, and a position 90° displaced from the shown position, in which the pedestal portion 322 lies substantially in a horizontal plane. A boss 324 on the body portion 320 is adapted to strike an upstanding portion 326 on the base 316 accurately to define the upright, working position of the wheel dresser 315. A handle 328, affixed to the pedestal portion 322, facilitates the rotation of the body portion 320 between its two positions.

A micrometer barrel 330 is mounted in the upper end of the pedestal portion 322 and is adapted to precisely advance a holder 332, and hence a cutting diamond 334. The selected position of the diamond 334, as established by the setting of the micrometer 330, is maintained by means of a set screw 336.

The wheel dresser 315 is mounted upon the reciprocating table 22 (Figs. 1 and 8), the slots in the base 316 thereof (Fig. 4) permitting a rough initial adjustment in accordance with the size of the grinding wheel 58. The wheel dresser should be in its upright position, as represented in Fig. 4, only during the dressing operation and should be lowered so that it will not strike any portion of the spindle assembly 82 (Fig. 8) during the manual or automatic grinding operation. As insurance that the wheel dresser 315 will not be inadvertently left in its upright position and damage any portion of the equipment, means such as a stop 349 (Fig. 8) may be mounted upon the body casting 62 in an appropriate position to strike the wheel dresser body 320 or pedestal 322 and thereby rotate the dresser to its horizontal position if the wheel dresser is in its upright position when the table 22 is moved beyond the point where dressing could occur.

The manner of employing the wheel dresser 315 in conjunction with the previously described automatic cross-feed mechanism to perform repetitive precision grinding operations will best be perceived from a description of the preferred method of employing the equipment to obtain the desired result. Assuming the equipment to be in the position shown in Fig. 1 of the drawings, the adjusting screw 250 (Fig. 3) is adjusted to establish the desired feed rate and then the ratchet feed pawl 256 (Fig. 3) is disengaged from the ratchet 264 by depressing the integral lever 257, thereby disabling the automatic cross-feed. One of the workpieces to be bored is inserted in the chuck 14 (Fig. 1) and the table feed mechanism is set to the proper position. Assuming that the length of the workpiece to be ground is sufficiently small so that the reciprocator may be employed, the stop 44 and the pawl 46 are positioned to the requisite position and length of stroke, and the cam 200 (Fig. 2) is adjusted in position to actuate the rocker arm 202 at the appropriate time. While this position may be selected so that the incremental advance of the cross-feed mechanism will occur at any point in the stroke, it has been found preferable to adjust the cam 200 so that this incremental advance occurs at the full depth of stroke, i. e., when the table 22 is at its most rightward position in its cycle. The knob 292 (Fig. 6) is rotated to set the cam 150 in the final dwell position, i. e., so that the cam follower 148 is engaging that portion of the cam surface between lines 286 and 276.

After these preliminary steps, the workpiece is manually ground to finished size, manually controlling the cross-feed by means of the cross-feed wheel 63. After the workpiece is accurately ground to its finished size, the workhead 16 is moved away from the grinding wheel by traversing the table 22 to the left by means of the hand wheel 30, and the knob 292 is again rotated to set the cam 150 (Fig. 6) to the "dress" position, as shown. The wheel dresser 315 is then rotated to its operative position and the micrometer barrel 330 (Fig. 4) thereof is adjusted until the diamond 334 just touches the grinding wheel 58 (Fig. 1). It will be perceived that at this instant the point of the diamond 334 is precisely positioned in predetermined relationship with the forwardmost portion of the inner surface of the ground workpiece, i. e., the distance between the longitudinal axis of the chuck 14 and the diamond 334 has been set to a precise relationship with the internal radius of the correctly ground workpiece.

The wheel 58 is preferably dressed at this time by advancing the grinding wheel 58 into the diamond approximately one thousandth of an inch by turning the cross-feed wheel 63. The second workpiece is then inserted in the chuck 14, the ratchet feed pawl 256 (Fig. 3) is re-engaged, and the adjusting knob 292 (Fig. 6) is rotated to bring the "load" portion of the surface of the cam 150 into engagement with the cam follower 148. The reciprocator 40 is then engaged by depressing the handle 50 (Fig. 2) to bring the pawl 46 into operative position,

and the upper end of the bellcrank 40 is trapped between the stop 44 and the pawl 46. The control switches are then set to automatic operation, after which the machine will automatically grind the second workpiece to finished size. It will be observed that if for any reasons there has been error in the setting, as determined by measuring the internal diameter of the second workpiece, compensation may readily be made by turning the micrometer barrel 330 (Fig. 4) of the wheel dresser 315 the appropriate amount in the appropriate direction.

If it is desired to dress the grinding wheel 58 each grinding operation for precision grinding, or otherwise whenever it is desired to dress the wheel, this operation should be performed while the cam follower 148 is engaging the "dress" portion of the surface of the cam 150 (Fig. 6), as shown.

A control panel 350 may be mounted upon the front of the machine, carrying a plurality of switches SW1 to SW4 by means of which control may be exercised over the several motors employed in the apparatus. For example, switch SW1 may control the table drive motor 18, switch SW2 may control the workhead motor 32, switch SW3 may control the automatic sizing unit spindle motor 92, and switch SW4 may control the coolant pump motor 54.

As is represented in Fig. 11 of the drawings, each of the switches SW1, SW2, and SW4 is adapted to be placed in any one of three positions: an upper position for manual operation of the machine, a lower position for automatic operation of the machine, and a center, "off," position, each of those switches being shown in the latter position in Fig. 11 of the drawings. Switch SW3 has but an upper "on" and a lower "off" position.

In the arrangement of Fig. 11 it is assumed that lines L1 to L3 are connected to a suitable source of three-phase power. The voltage appearing between conductors L2 and L3 is applied to the primary winding of a step-down transformer T1, inducing an alternating voltage in the secondary winding of that transformer, and between conductors L4 and L5, of appropriate magnitude for the control purposes.

If the table-motor controlling switch SW1 is moved upwardly to the manual-control position, the voltage on conductor L4 is applied through that switch to the contacts of limit switch LS3. While limit switch LS3 is not disclosed in its mechanical details in Figs. 1 to 10 of the drawings, since those details form no part of this invention, it may be noted that mechanical linkage is or may be provided which is adjustable to define two limit positions of motion of the table 22 for power reciprocation of that table. When the table is at its selected leftmost position, limit switch LS3 is moved upwardly (Fig. 11) to complete an energizing circuit for relay TF which closes its contacts TFa to TFc to cause the table motor 32 to rotate in an appropriate direction to move table 22 to the right (Fig. 1). When the table 22 reaches its selected right-hand limit position, the mechanical linkage moves limit switch LS3 to its lower position (Fig. 11) to release relay TF and to operate relay TR, whereupon relay TR closes its contacts TRa to TRc to cause table motor 32 to be rotated in the opposite direction to move table 22 back to the left (Fig. 1). When this power feed mechanism is not being employed, i. e., whenever the table 22 is being reciprocated either by hand or by the reciprocator mechanism 40, the limit switch LS3 is moved to its upper position (Fig. 11) so as continuously partially to complete an energizing circuit for relay TF. However, when the table is being manually reciprocated by hand-wheel 30 (Fig. 1) switch SW1 is placed in its "off" position, as shown, so that relay TF cannot operate.

When the head-motor controlling switch SW2 is moved to its upper, manual-control position, control of the head relay H is bestowed upon on-off switch SW5 which may be conveniently located upon the machine. When relay H is operated, its contacts Ha to Hc are closed to apply

the three-phase alternating voltage between conductors L1 to L3 to the head motor 18.

The spindle motor 92 is controlled by on-off switch SW3 and relay S. During either manual or semiautomatic operation of the mechanism, motor 92 runs continuously.

When the pump-motor controlling switch SW4 is moved upwardly to its manual-control position, relay P is operated to cause pump motor 54 continuously to rotate.

To prepare for semiautomatic operation of the machine, switch SW3 is moved to its closed position, and switches SW1, SW2, and SW4, are moved downwardly to their automatic-control positions.

As previously described, limit switch LS1 (Fig. 1) is momentarily tripped whenever table 22 is moved back to the right from its leftmost limit position. It is assumed that limit switch LS1 contains a single normally open contact (Fig. 11).

The other controlling limit switch LS2 (Fig. 8) is assumed to be provided with a single normally closed contact which is opened whenever actuator 192 is forced inwardly by either projecting finger 184 or projecting finger 186. The timing discs 176 and 178 are, in the preferred arrangement, so oriented that the projecting finger 184 strikes the actuator 192 at the commencement of the dress interval (Fig. 6), and that the projecting finger 186 strikes the actuator 192 of switch LS2 at the beginning of the load position.

In the circuits of Fig. 11, limit switches LS1 and LS2 are shown in a position corresponding to the position of the machine as represented in Figs. 1 to 10 of the drawings, that is, the table 22 (Fig. 1) is not at its leftward-most position, so that limit switch LS1 is in its normally open position, and neither projecting finger 184 nor 186 (Fig. 8) is in engagement with actuator 192 of limit switch LS2 so that limit switch LS2 is in its normally closed position (Fig. 11).

To institute semiautomatic operation of the machine, table 22 is traversed to its leftmost position to facilitate loading of the workpiece, and is then traversed to the right by the handwheel 30. During the course of this travel, limit switch LS1 (Fig. 11) is momentarily closed. Upon its closure, a circuit is completed from conductor L4, the lower pair of contacts of switch SW2, limit switch LS2 (No. 1 contacts), conductor L6, limit switch LS1, winding of relay TD2, to conductor L5. Relay TD2 is a time delay relay having one normally open instantaneous closing contact TD2*i* and one normally open time-delay contact TD2*d*. Immediately upon the operation of relay TD2, its contacts TD2*i* are closed to complete a holding or sealing circuit for unit TD2 through that instantaneous contact TD2*i*, and through normally and now closed contacts He to conductor L6. Consequently, time delay unit TD2 remains operated when limit switch LS1 again opens after its momentary closure.

After the preselected time interval, contacts TD2*d* are closed to complete a circuit from conductor L6, contacts TD2*d*, conductor L7, lower contact of switch SW1, upper contact of limit switch LS3 and through the winding of relay TF to conductor L5 whereupon relay TF is operated to initiate the rotation of table motor 32. Additionally, the voltage on conductor L7 is applied through the middle contact of switch SW2 to energize relay H and hence to institute rotation of the head motor 18, and through the lower contact of switch SW4 to start pump motor 54.

Relay H, in operating, closes its normally open contacts Hd which completes a holding or sealing circuit for relay H to conductor L6 and which completes holding or sealing circuits for relays TF and P by interconnecting conductors L6 and L7 through the middle contact of switch SW2. Hence, the head motor 18, the table motor 32 and the pump motor 54 continue to rotate even though contact TD2*d* is opened.

Means are provided to open contact TD2*d* by releasing time delay unit TD2 in order to restore that relay to normal in preparation for its repeated function in the next

cycle. This means comprises the normally closed contact He of relay H which opens when relay H operates to interrupt the locking or sealing circuit for relay TD2, whereupon time delay relay TD2 releases and contacts TD2*d* are opened.

It will be appreciated that the function of unit TD2 is to interpose a delay after limit switch LS1 (Fig. 1) is tripped to allow the operator time to easily re-engage the reciprocator 46 between the stop 44 and the latch 46.

The cycle of operation continues until the cam 150 (Fig. 6) reaches its "dress" position, as shown. At the beginning of this period, the projecting finger 184 (Fig. 8) on timing disc 176 will strike and move the actuating member 192 of limit switch LS2, opening that limit switch.

When the No. 1 contacts of limit switch LS2 are opened (Fig. 11), the sealing or holding circuits for relays H, TF and P are interrupted, those relays release, and the head motor 18, the table motor 32 and the pump motor 54 stop.

Upon this indication, the operator releases the latch 46 (Fig. 1), traverses the table to the left, and proceeds to press the wheel, if dressing each cycle is performed. The operation of the workhead motor 18, of the table drive motor 32 and of the pump motor 54 is reinstated by limit switch LS1. However, it is possible that the termination of the operation of the table reciprocator will occur while finger 184 (Fig. 8) is engaging actuator 192

of limit switch LS2 in which case limit switch LS2 (Fig. 1) will remain separated from its No. 1 contact and the motors cannot be re-energized. To avoid this possibility, limit switch LS2 is provided with a No. 2 normally open contact which is closed when either finger 184 or 186 (Fig. 8) strikes the actuating arm 192. Upon the closure of limit switch LS2 to its No. 2 contact, a circuit is completed to energize time delay unit TD1. Time delay unit TD1 is a time delay relay which functions to so

modify the circuit conditions that after its delay period it is as if limit switch LS2 were again closed to its No. 1 contact even though limit switch LS2 has not been released by finger 184 or 186. Thus, a preselected delay interval after the energization of relay TD1, contacts TD1*a*, connected in shunt of the No. 1 contacts of limit switch LS2, are closed. Hence, the subsequent closure of limit switch LS1 will re-energize motors 32, 18 and 54.

The resultant reciprocation of the table will step the timing drums 176 and 178 (Fig. 8), limit switch LS2 will reclose to its No. 1 contact and time delay unit TD1 will become de-energized.

The cycle then proceeds to completion, its termination being denoted by the engagement of the cam follower 148 (Fig. 6) with the "load" portion of the surface of the cam 150. At this point, projecting finger 186 on timing disc 178 will open limit switch LS2 and the rotation of the chuck 14 (Fig. 1) and the reciprocation of the table 22 will be terminated as before. This will signal the operator to release latch 46 and traverse the table 22 to the left by handwheel 30 preparatory to removing the workpiece and reloading the chuck.

While it will be apparent that the embodiment of the invention herein disclosed is well calculated to fulfill the object above stated, it will be appreciated that the invention is susceptible to modification, variation and change without departing from the proper scope or fair meaning of the subjoined claims.

What is claimed is:

1. In a grinding machine or the like, a body member, a spindle assembly, pivot means for pivotally supporting said spindle assembly upon said body member, spring means tending to pivot said spindle assembly in one direction upon and relative to said body member, means including a pair of spaced-apart pins bearing laterally against said spindle assembly mutually operable to maintain a balanced pressure against said spindle assembly and to establish an adjustable limit position to movement of said spindle assembly in said one direction, and means

engageable with both of said pins for concurrently shifting the position of both of said pins relative to said body member for pivoting said spindle assembly relative to said body member.

2. In a grinding machine or the like, a body member, a spindle assembly, pivot means for pivotally supporting said spindle assembly upon said body member, spring means tending to pivot said spindle assembly in one direction upon and relative to said body member, means including a pair of spaced-apart pins both at one side of said spindle assembly for establishing an adjustable limit position to movement of said spindle assembly in said one direction, and power driven means for concurrently and identically shifting the positions of both of said pins relative to said body member for pivoting said spindle assembly relative to said body member.

3. In a grinding machine or the like, a body member, a spindle assembly, means including a spindle-assembly housing movably supporting said spindle assembly relative to said body member, spring means tending to move said spindle assembly in one direction relative to said body member, a shaft rotatably supported in said body member, means for rotating said shaft, a pair of spaced-apart actuating surfaces integral with said shaft, and a pair of parallel actuating pins engaging said surfaces and said housing.

4. In a grinding machine or the like, a housing, a spindle assembly mounted in said housing, a body member, a shaft supported in said body member, means for rotatively supporting said housing upon said shaft, the longitudinal axes of said shaft and said spindle assembly lying in spaced parallelism with one another, a pair of spaced-apart, parallel actuating pins engageable with said housing, means for moving said pins, and spring means acting along a line parallel with and intermediate said pins for maintaining said housing in engagement with said pins.

5. In a grinding machine or the like, a body member, a spindle assembly movably supported by said body member, a cam shaft rotatably supported by said body member, means including said cam shaft for moving said spindle assembly relative to said body member, a table, means for reciprocating said table, and means actuated by said table for rotating said cam shaft.

6. In a grinding machine or the like, a base, a table, means for reciprocating said table, a rocker arm mounted on said base, a cam on said table engageable with said rocker arm, a spindle assembly, a shaft, means including said shaft for moving said spindle assembly transversely of said table, and means actuated by said rocker arm for rotating said shaft.

7. In a grinding machine or the like, a base, a table, means for reciprocating said table, a rocker arm mounted on said base, a cam on said table engageable with said rocker arm, a spindle assembly, a shaft, means including said shaft for moving said spindle transversely of said table, and means actuated by said rocker arm for rotating said shaft comprising a ratchet mounted on said shaft, a pawl engageable with said ratchet, and linkage means actuated by said rocker arm for reciprocating said pawl.

8. In a grinding machine or the like, a body member, a spindle assembly movably supported by said body member, a cam shaft rotatably supported by said body member, means including said cam shaft for moving said spindle assembly relative to said body member, a table, means including a motor for reciprocating said table, means actuated by said table for rotating said cam shaft, a timing drum mounted on said cam shaft, a switch actuated by said timing drum, and means controlled by said switch for deenergizing said motor.

9. In a grinding machine or the like, a body member, a spindle assembly movably supported by said body member, a cam shaft rotatably supported by said body member, means including said cam shaft for moving said spindle assembly relative to said body member, a table, means

including a motor for reciprocating said table, means actuated by said table for rotating said cam shaft, a timing drum mounted on said cam shaft, a switch actuated by said timing drum, means controlled by said switch for deenergizing said motor, and means effective a selected interval after the actuation of said switch for disabling said switch to control said motor.

5 10. In a grinding machine or the like, a base, a table movably supported on said base, latch means on said table, 10 a motor, table reciprocator means driven by said motor and selectively engageable with said latch means, manually controlled means for traversing said table between a position at which said reciprocator means is engaged with said latch means and a limit position at which said reciprocator means is disengaged from said latch means, and switch means actuated when said table is traversed from said limit position for energizing said motor.

15 11. In a grinding machine or the like, a base, a table movably supported on said base, latch means on said table, 20 a motor, table reciprocator means driven by said motor and selectively engageable with said latch means, manually controlled means for traversing said table between a position at which said reciprocator means is engaged with said latch means and a limit position at which said reciprocator means is disengaged from said latch means, switch means actuated when said table is traversed from said limit position, and means effective a timed interval after said switch means is actuated for energizing said motor.

25 12. In a grinding machine or the like, a base, a table movably supported on said base, latch means on said table, 30 a motor, table reciprocator means driven by said motor and selectively engageable with said latch means, manually controlled means for traversing said table between a position at which said reciprocator means is engaged with said latch means and a limit position at which said reciprocator means is disengaged from said latch means, switch means actuated when said table is traversed from said limit position, and means effective a timed interval after said switch means is actuated for energizing said motor.

35 13. In a grinding machine or the like, a base, a table movably supported on said base, latch means on said table, 35 a motor, table reciprocator means driven by said motor and selectively engageable with said latch means, manually controlled means for traversing said table between a position at which said reciprocator means is engaged with said latch means and a limit position at which said reciprocator means is disengaged from said latch means, a work-head including a motor mounted on said table, and switch means actuated when said table is traversed from said limit position for energizing both of said motors.

40 14. In a grinding machine or the like, a base, a table movably supported on said base, latch means on said table, 40 a motor, table reciprocator means driven by said motor and selectively engageable with said latch means, manually controlled means for traversing said table between a position at which said reciprocator means is engaged with said latch means and a limit position at which said reciprocator means is disengaged from said latch means, a body member supported on said base, a cam shaft rotatably supported by said body member, means actuated by said table for rotating said cam shaft, a timing drum mounted on said cam shaft, a first switch actuated by said timing drum, a second switch actuated when said table is traversed from said limit position, and circuit means including said switches for controlling said motor.

45 15. In a grinding machine or the like, a base, a table, means for reciprocating said table, a rocker arm mounted on said base, a cam on said table engageable with said rocker arm, a spindle assembly, a shaft, means including 50 said shaft for moving said spindle transversely of said table, a ratchet mounted on said shaft, a pawl engageable with said ratchet, linkage actuated by said rocker arm for reciprocating said pawl, and means for adjusting the length of stroke of said pawl.
